G. Smith and H. Brown, of Philadelphia, Penn.

Deors. to

Abbott and Hobbs, of same place.

Letter Patent No. 4428. Dated Oct. 6. 1868.

Design for a Furnace Stove.

The schedule referred to in these Letters Patent and making part of the same.

To all whom it may concern:

Be it known that we, Garrettson Smith, and Henry Brown, of the City and County of Philadelphia, State of Pennsylvania, have invented or produced a new and original design for a Furnace; and we do hereby declare the accompanying drawing, with the following explanation of the same, to form a full, clear and exact description of the said Design.

On reference to the drawing. A is the fire-pot, the outer surface of which is ornamented by vertical flutings; the said fire pot resting on the base plate B, which is bordered by a heavy plain moulding $\frac{1}{2}$.

Surrounding the top plate C, is an ornamental beaded moulding $\frac{1}{2}$.
